RAILWAY COUPLER BUTT END AND FOLLOWER

Loree Elwyn Furniss, Groveport, Ohio, assignor to The Buckeye Steel Castings Company, Columbus, Ohio

Application February 10, 1956, Serial No. 564,819

15 Claims. (Cl. 213—72)

The present invention relates to the structure of the butt end of the stem of a railway coupler and to the configuration of the forward face of the front follower of a draft rigging for cooperation with the rear end of the coupler stem and the invention has utility in connection with railway couplers and appliances therefor and particularly those of the interlocking type used in freight service.

The interchange requirements of the Association of American Railroads allow a difference of three inches in coupler heights between empty and loaded freight cars. The butt end construction of interlocking couplers for freight service now in use and cooperating portions of the front follower and the coupler carrier have been such as to maintain a coupler carried by a fully loaded car within the prescribed limit of the coupler carried by an empty or unloaded vehicle. The impact created in the coupling of railway cars equipped with a prior type of couplers when horizontally displaced to such an extent develops resultant forces which are directed in undesired directions. The momentum of one car moving into a coupling position with another produces a resultant force which is directed downwardly on the loaded car body and a resultant force which is directed upwardly on the empty or unloaded vehicle body. When the kinetic energy dissipated in the coupling operation is great enough the resultant force applied to the empty car lifts the vehicle body off its truck. The lifting action is restricted only when the couplers engage the boundary of the striker openings.

It is an object of the present invention to provide the butt end of the stem of a railway coupler with a shape for cooperation with an improved front follower so that in the mating of a coupler carried by a fully loaded vehicle with a coupler carried by an unloaded vehicle the resultant forces developed are in reverse directions with respect to prior coupler assemblies so that a resultant force acting on the empty car body structure is directed downwardly thus preventing the lifting of the car body and avoiding the possibility of the railway vehicle body being lifted from its truck.

Another object of the present invention is to provide the rear end of a coupler stem and its cooperating follower with such a shape that the resultant force developed in the draft rigging during a coupling operation is such that a downward force is developed on the sill structures of the car body arranged at the highest level while an upwardly directed resultant force is developed in the draft attachment of the vehicle body arranged at a lower level and at the same time to retain the retarding characteristics against horizontal swivel of the coupler stem beyond prescribed limits.

A further object of the invention is to provide a forward face on the front follower of a railway draft rigging which is adapted to be engaged by a generally transverse conical surface on the butt end of the coupler stem after predetermined free angling of the coupler in any direction and the assembly thereafter resiliently re-

2

tards swiveling of the coupler stem in all directions beyond the limit as predetermined by the angular disposition of the conical surface.

A still further object of the invention is to simplify the construction of the rear end of the coupler stem and the forward face of the front follower and to reduce the cost of manufacture and particularly the gauging of the surfaces of both the butt end of the coupler shank and the forward face of the follower while improving the operational functions of the draft assembly.

Other and further objects and features of the invention will be appreciated and become apparent to those skilled in the railway coupler art as the present disclosure proceeds and upon consideration of the accompanying drawings and the following detailed description wherein an exemplary embodiment of the invention is disclosed.

In the drawings:

Fig. 1 is a sectional plan view of the rear portion of a coupler stem and a follower therefor exhibiting the invention taken on the horizontal center line of the draft rigging and showing the cooperation of the parts in limiting free horizontal swiveling of the coupler.

Fig. 2 is a similar sectional view showing the position of the parts when the coupler is swiveled horizontally beyond the unrestrained limits.

Fig. 3 is a plan view of the butt end of a coupler stem embodying the invention.

Fig. 4 is a side elevational view showing the profile of the rear end portion of the coupler stem.

Fig. 5 is an end elevational view of the butt of the coupler stem.

Fig. 6 is an elevational view of the forward face of a follower exhibiting invention and designed for cooperation with the coupler stem.

Fig. 7 is a side elevational view of the follower.

Fig. 8 is a plan view of the front follower.

Fig. 9 is a side elevational view of two couplers exhibiting the invention with parts of their draft riggings shown in section and illustrating the development of advantageous resultant forces.

Fig. 10 is a similar view depicting the undesired resultant forces with prior couplers and draft attachments therefor.

The invention is directed to the construction of the butt end of the stem of a railway coupler which produces a number of desirable results and the invention further relates to the structure shape of the forward face of the front follower which cooperates with the butt end of the coupler to provide for the development of downward acting force on the body of a railway vehicle when it is at a higher level than another railway vehicle body during a coupling operation and the butt end and the follower further serve to retard swiveling of the coupler after a limited extent of free angling and further provides for a simplification of the structure thereby reducing the manufacturing costs and reducing the gauging operations at the butt end of the stem and the forward face of the follower while improving the operational functions of the draft rigging.

Referring to the drawings there is shown at 11 the stem of a coupler of the interlocking type provided with a butt end embodying the invention. This portion of the coupler is normally accommodated in the striker 12 having walls 14 and 16 defining the horizontal extremities of the opening in the striker casting. All parts and structural features of the draft rigging are of conventional design and construction except for the butt end of the coupler stem 11 and the forward face of the front follower shown at 17 and the characteristics of these elements which provide new results will be appreciated as the disclosure proceeds.

The butt end of an existing interlocking coupler for freight service has been provided with cylindrical surfaces generated about a horizontal axis coinciding with the center line of the coupler shank. The butt end of a coupler embodying the present invention is devoid of such cylindrical surfaces but includes the conventional centrally disposed spherical surface portion 18 which provides a rearwardly projecting convex surface. An important difference of the butt end structure of the present invention pertains to the character and disposition of the shoulder or surface 19 around the convex spherical portion 18. The shoulder 19 is continuous around the spherical portion 18 and this surface 19 is arranged generally transversely of the center line of the coupler stem 11. The surface providing the shoulder 19 is of conical shape, the vertex of which is located on the center line of the coupling stem 11 with the apex disposed forwardly of the rearmost center of the spherical surface 18. In the embodiment illustrated the vertex of the cone about which the surface forming the shoulder 19 is generated is disposed on the center line of the coupler stem forwardly of the rearmost portion of the spherical surface 18 by one-half an inch. The conical surface 19 arranged around the perimeter of the spherical surface 18 is disposed so as to slope four degrees from a vertical plane through the apex of the cone in all directions forwardly from the vertex. Such an angular disposition of the surface providing the shoulder 19 is indicated in Fig. 3.

The cylindrical surfaces previously provided on the butt end of the stem of an interlocking coupler for freight car service are not employed in the present invention and the areas indicated at 23 in Fig. 5 are of conical shape as hereinabove described and form part of the continuous shoulder 19 about the perimeter of the convex spherical portion 18. The generally transverse surface forming the shoulder 19 is more conveniently formed in a manufacturing operation and gauging of the previously employed cylindrical surfaces on the butt end of the stem is no longer necessary. The conical surface forming the shoulder 19 forms a structural characteristic which contributes to new results and desired functions in operation of the coupler as hereinafter described. The coupler stem 11 in other respects remains unaltered and is adapted for cooperation with the yoke 15 and yoke pin 20 in a conventional and known manner.

The forward face of the front follower 17 is designed for cooperation with the butt end hereinabove described and differs from the prior front follower in that the two cylindrical concave seats previously employed are no longer necessary and are avoided. A front follower embodying the invention includes a spherical shaped cavity or seat 26 for receiving the spherical convex portion 18 on the butt end of the coupler stem 11 so as to provide for vertical and horizontal angling of the coupler. The follower 17 is provided with a surface 27 which is arranged in a single plane and surrounds the spherical concave seat or cavity 26. The surface 27 is arranged at right angles to the center line of the draft rigging and is disposed forwardly of the rearmost portion of the spherical seat 26. In the embodiment illustrated the surface 27 is disposed one-half an inch forwardly from the bottom of the cavity 26 as measured along the center line of the draft rigging. The front follower 17 is arranged transversely of the draft rigging between the resilient draft gear diagrammatically shown at 29 in Fig. 1 and the front draft lugs 31. The flat plane surface 27 normally lies in a plane at right angles to the center line of the draft rigging. Other portions of the front follower are like those of the prior devices including a rear face 25 substantially parallel to the front surface 27.

In operation and when one railway vehicle equipped with a coupler having a butt end on the stem thereof as herein disclosed is mounted in association with the follower described and the vehicle body is empty or ar-

ranged at a high elevation its coupler is supported by a coupler carrier of a known type such as shown at 32 in Fig. 9. Even in the absence of the coupler carrier the coupler shown at the left in Fig. 9 is free to angle downwardly only until the conical surface forming the shoulder 19 and that area thereof below the spherical convex portion 18 engages the plane flat surface 27 of the front follower in the area under the spherical cavity 26. The coupler stem 11 is also free to angle upwardly until the conical surface 19 in area above the spherical portion 18 engages the flat face 27 on the front follower. In the embodiment disclosed the free downward or upward angling of the coupler stem 11 is permitted during swiveling of two inches of the coupler from the longitudinal center line of the draft rigging as measured at the coupling line. Thereafter any further downward or upward swinging movement of the coupler head is restrained by engagement of the lower or upper area of the conical shoulder 19 with corresponding portions of the flat surface 27 of the front follower.

The butt end on the coupler stem 11 and the forward face of the front follower shaped as herein disclosed permits initial free horizontal angling of the coupler without restraint. In the specific embodiment disclosed the coupler may swing laterally a distance of two inches measured along the coupling line from the center line of the draft rigging before a lateral portion 34 of the conical shoulder 19 engages a corresponding portion of the surface 27 on the front follower. Such a position of the parts is shown in Fig. 1. The coupler stem may be swiveled horizontally to a greater angular position until the side 36 of the coupler stem engages the wall surface 14 of the striker as shown in Fig. 2. During such additional horizontal angling of the coupler the front follower 17 is cammed to an angular position as shown in Fig. 2 by engagement of the outer extremity of the conical surface 19 with the flat face 27 of the follower and in the area indicated at 37. During swinging movement of the coupler stem horizontally beyond the position shown in Fig. 1 to the position shown in Fig. 2 the reaction of the resilient draft gear 29 yieldably resist horizontal swinging of the coupler. In the particular embodiment disclosed the horizontal angling of the coupler in the position shown in Fig. 2 amounts to six and one-half inches as measured at the coupling line.

An important advantageous result is obtained when two couplers and draft appliances of the type herein disclosed are moved towards a position for mating the couplers. The coupler and draft rigging shown at the left in Fig. 9 represents the position of these parts when carried by a railway vehicle having its body located at a higher level than the car body equipped with the draft rigging and coupler exhibiting the invention and shown at the right in Fig. 9. When the two vehicles arranged in different elevations as depicted have relative movement towards each other in carrying out a coupling operation the force derived from such momentum is along the line 41 in the direction of the arrows 42 and 43 of Fig. 9. When the centers of the spherical seats 26 are displaced vertically sufficiently this force is taken in the area 38 at the right in Fig. 9 and in the area 46 at the left in Fig. 9 on the shoulders 19 of the coupler stems 11 where they contact the flat surfaces 27 of the front followers. A resultant force is developed directed downwardly as shown by the arrow 47 at the left in Fig. 9 which urges the draft rigging and the sill structure carried by the vehicle body downwardly. The other resulting force indicated by the arrow 48 is directed upwardly as shown at the right in Fig. 9. The resultant force 48 acts upwardly on the draft rigging and the body sills of the vehicle body occupying the lower level. Since the resultant 47 is directed downwardly a force is developed to move the car body having the higher level position downwardly and thereby avoids lifting it from its truck.

These new results will be further appreciated and understood by consideration of Fig. 10 wherein the butt ends of the stems of the couplers and the front followers are of a prior type. In this arrangement the energy provided by movement of one or both of the vehicles in carrying out a mating of the couplers creates a force which is along the line 51 in the directions of the arrows 52 and 53. This kinetic energy develops resultant forces which are directed in undesirable directions when the center lines of the couplers are vertically displaced by three inches. One resulting force indicated by the arrow 54 is upwardly on the vehicle body which is arranged at the higher level. The other resultant force indicated by the arrow 56 is downwardly in its action on the loaded car or the vehicle body located at the lower level. When the resultant force 54 is sufficiently large the sill structure at the left in Fig. 10 and the body of the vehicle is lifted to such an extent as to free the body from the truck.

While the invention has been described with reference to specific structural features and with regard to specific angular disposition and dimensions of certain surfaces it will be appreciated that changes may be made in the details as well as the organization. Such modifications and others may be made without departing from the spirit and scope of the invention. The features may be incorporated in couplers and draft riggings for service other than freight hauling.

What I claim and desire to secure by Letters Patent is:

1. In a railway draft rigging, a coupler and a stem therefor, a butt end on said stem having a centrally disposed rearwardly directed convex spherical surface portion and a shoulder forming the rear end of said stem around said spherical portion arranged generally transversely of the center line of the stem, said shoulder being of conical formation and inclined forwardly in proceeding radially outwardly from the perimeter of said spherical portion, a follower adjacent said butt end, said follower having a spherical cavity in a forward face receiving said spherical portion, and a forward surface on said follower surrounding said spherical cavity arranged in a single plane substantially at right angles to the axis of the draft rigging.

2. In a railway draft rigging, a coupler and a stem therefor, a butt end on said stem including a rearwardly directed convex spherical surface portion and a generally transverse surface around said spherical surface portion, said surface being of conical formation in all areas radially outward of said spherical portion and inclined forwardly in proceeding outwardly from the perimeter of said spherical portion, a front follower having a spherical cavity therein receiving said spherical portion, and a forward surface on the follower surrounding said spherical cavity arranged in a single plane substantially at right angles to the axis of the draft rigging.

3. In a railway draft rigging, a coupler including a stem, a surface forming part of the rear end of said stem arranged generally transversely of the center line of the stem, said surface being of conical formation with the vertex thereof on the center line of said stem, said surface being inclined forwardly in proceeding outwardly towards the top and the sides and the bottom of the stem, a spherical convex portion having its center on the center line of said stem and projecting rearwardly beyond said surface, a front follower having a spherical concave cavity therein receiving said spherical convex portion, and a forward surface on the front follower surrounding said spherical cavity arranged in a single plane substantially at right angles to the axis of the draft rigging.

4. In a draft rigging according to claim 3, wherein the vertex for said surface is disposed forwardly of the rear end of the spherical convex portion.

5. In a draft rigging according to claim 3, wherein the surface of conical formation is inclined at an angle of about four degrees with reference to a plane disposed at right angles to the center line of the coupler stem.

5. In a draft rigging according to claim 3, wherein the surface of conical formation is inclined at the same angle with reference to a plane disposed at right angles to the center line of the coupler stem as the required angle of free swivel of the coupler stem.

7. In a draft rigging according to claim 3, wherein the apex of said surface is located approximately one-half inch forwardly of the rear end of the spherical convex portion.

8. In a draft rigging according to claim 3, wherein the apex of said surface is located substantially in the plane of the forward surface on the front follower.

9. In a draft rigging according to claim 3, wherein the surface of conical formation is inclined at an angle of about four degrees with reference to a plane disposed at right angles to the center line of the coupler stem, and the apex of said surface is disposed one-half inch forwardly of the rear end of said spherical convex portion.

10. A butt end construction for the stem of a railway 25 coupler comprising, a convex spherical portion projecting rearwardly from the stem, and a shoulder surrounding said spherical portion of conical formation with the surface thereof inclined forwardly of the coupler stem in proceeding outwardly from the perimeter of said spherical portion in all radial directions.

11. A butt end construction for the stem of a railway coupler comprising, a surface arranged generally transversely of said stem at the rear end thereof, said surface being of conical formation inclined forwardly of the coupler stem in proceeding outwardly towards the sides and top and bottom of the stem, and a spherical portion on the stem having its center aligned with the axis of the stem and a convex area projecting rearwardly from said surface.

12. A butt end construction for a railway car coupler according to claim 10, wherein the vertex about which the surface of conical formation is generated coincides with the axis of the coupler stem.

13. A butt end construction for a railway car coupler according to claim 11, wherein the vertex about which the surface of conical formation is generated coincides with the axis of the complex stem and is disposed forwardly of the rear end of the convex area.

14. A front follower for a railway draft rigging comprising, a plate member, a rear face on said member, a continuous forward surface on said member substantially parallel to said rear face and lying in a single plane, said forward surface having a concave cavity of segmental spherical shape within a central portion thereof, and the area of the mouth of said cavity measured at the plane of said surface being less than the area of said surface.

15. A front follower for a railway draft rigging comprising, a plate member, a rear face on said member, a continuous forward surface on said member substantially parallel to said rear face and lying in a single plane, said forward surface having a concave cavity of segmental spherical shape within a central portion thereof, the area of the mouth of said cavity measured at the plane of said surface being less than the area of said surface, and said surface being disposed approximately one-half an inch forwardly of the deepest portion of said cavity.
